(57) **CLAIM**

The ornamental design for a ring, as shown and described.

DESCRIPTION

FIG. 1 is a perspective view of a ring;

FIG. 2 is a left side perspective view thereof;

FIG. 3 is a right side perspective view thereof;

FIG. 4 is a front perspective view thereof;

FIG. 5 is a bottom perspective view thereof;

FIG. 6 is a top perspective view thereof;

FIG. 7 is a perspective view thereof in an open position; and,

FIG. 8 is a top view thereof.

The broken lines illustrate portions of the ring and form no part of the claimed design.
